UNITED STATES PATENT OFFICE

98,901

DESIGN FOR A GLOVE

Max W. Winkler, Bethlehem, Pa., assignor to Queen City Textile Corporation, Allentown, Pa.,
a corporation of Pennsylvania

Application January 7, 1936, Serial No. 60,464

Term of patent 3½ years

To all whom it may concern:

Be it known that I, Max W. Winkler, a citizen of the United States, residing at Bethlehem, in the county of Northampton and State of Pennsylvania, have invented a new, original, and ornamental Design for a Glove, of which the following is a specification, reference being had to the accompanying drawing, forming part thereof.

The front of the glove is of conventional form.

I claim:—

The ornamental design for a glove as shown and described.

MAX W. WINKLER.
